UNITED STATES PATENT OFFICE.

PETER GENDRON, OF TOLEDO, OHIO.

MACHINE FOR TRIMMING WIRE SPOKES.

SPECIFICATION forming part of Letters Patent No. 396,814, dated January 29, 1889.

Application filed October 17, 1888. Serial No. 288,358. (No model.)

To all whom it may concern:

Be it known that I, PETER GENDRON, a citizen of the United States, residing at Toledo, in the county of Lucas and State of Ohio, have 5 invented certain new and useful Improvements in Machines for Trimming Wire Spokes, of which the following is a specification, reference being had therein to the accompanying drawings.

10 This invention relates to new and useful improvements in a machine for trimming wire spokes, and the invention is especially designed to be used in the manufacture of such iron wheels in which the spokes are 15 formed of wire, and wherein the spokes have to be cut off at the ends at equal length after they are secured to the hub and before the rim of the wheel is secured thereto.

My invention consists in the peculiar construction and arrangement of the cutting devices for cutting off the ends of the spokes, and of a wheel-support adapted to permit of 20 adjusting the wheel in proper relation to the cutting device, and of revolving the wheel 25 so as to present the spokes successively to the cutting off devices, all as more fully herein-after described, and shown in the accompanying drawings, in which—

Figure 1 is a plan of my machine; Fig. 2, 30 a vertical central longitudinal section; Fig. 3, a cross-section on line *x* *x* of Fig. 1; and Fig. 4 is a detached perspective view of the cutting-off devices and the rotary wheel-support.

A is the bed of the machine, provided with 35 suitable legs and supporting at one end in suitable bearings, B, the horizontal drive-shaft C, which is provided at its outer end with the drive-pulley D and at its inner end with a rotary cutter, E. This rotary cutter is provided with a series of circumferential cutting-teeth, F, as shown in Fig. 3, *a* being the cutting-edge of each tooth, and this cutting-edge is concave to conform to the cross-section of a wire spoke. In close proximity to the inner 40 vertical face of this rotary cutter is secured, upon the bed of the machine, the stationary cutting-block G, the edge *b* of which forms the stationary cutting-edge, which operates in conjunction with the cutting-edges *a* of the 45 rotary cutter to trim the spokes. This cutting-block is detachably secured in a suitable manner to the knife-holder H, secured upon

the bed of the machine in front of the rotary cutter-head, as shown in Fig. 4.

I, Fig. 1, is a longitudinal slot through the center of the bed in the vertical axial plane of the cutter-head, and in this slot is slidably secured the wheel-support, which consists of the sliding bearing J, adapted to be adjusted back and forth within the slot and secured 60 therein by means of a suitable clamp-bolt, K. In this bearing is journaled a vertical stop-shaft, L, split through its center and tapered at its end *c*. Upon this stop-shaft is secured the dog M, which rests on top of the bearing J, and to the lower end of the stop-shaft is secured the cord-pulley N, and to an arm, O, Figs. 1 and 2, projecting laterally, is secured the cord-pulley P. Upon the shaft C of the rotary cutter-head is formed a suitable cord-pulley, Q, and vertically below this, underneath the bed, are secured the cord-pulleys R and S, and on the opposite end of the bed is secured to a slidingly-adjustable bearing, T, the cord-pulley U, all so arranged that by 75 means of the endless cord V, passing over these various pulleys, as shown, motion is transmitted from the cord-pulley Q on the shaft C to the revolving shaft L of the wheel-support. By means of the combination of the pulleys 80 N and P the wheel-support may be adjusted back and forth in the slot without altering the tension of the drive-cord.

The pulleys R and S, as will be well understood, are guide-pulleys to change the direction of the cord from vertical to horizontal, while the cord-pulley U at the end of the bed permits the tightening of the cord by means of the adjusting-screw W through the end of the bed, which screw engages into the sliding 90 bearing T, which carries the cord-pulley. A similar adjusting-screw, X, passing longitudinally underneath the bed, engages with the sliding bearing of the wheel-support, and thereby forms the means of adjusting the 95 wheel-support at any desired distance from the rotary cutter-head, said distance being marked by a scale, Y, on the edges of the slot I, and the indicator-hand Z on the sliding bearing permits of indicating the distance 100 accurately.

d is a guide-rail secured to the bed of the machine in the vertical plane of the cutter-head, and this is provided at its free end with

an incline, *e*, to guide the spokes downwardly into the cutting-teeth of the rotary cutter-head, and another guide-rail, *f*, is secured upon the bed to lead the spokes upwardly 5 into the teeth of the rotary cutter-head by means of its incline *g*. The guide-rail *d* is preferably curved above the cutter-head to form a guard therefor, as shown in Fig. 3.

In practice, the parts being arranged and 10 constructed substantially as shown and described, they are intended to operate as follows: The wheel, the spokes of which are intended to be operated upon by the machine, is engaged with its hub upon the shaft *L* of the wheel-support. This shaft is made to fit 15 the hub snugly, and by having it split, as described, the hub can be readily engaged with it without having any lost motion thereon. The dog *M* has its outer ends curved upwardly to engage between the spokes of the 20 wheel, and thereby revolves the wheel with the shaft *L* upon motion being given to the machine. It will readily be seen that the motion is communicated through the cord *V* 25 from the shaft *C* to the shaft *L* of the wheel-support, and the wheel being carried thereby will be revolved in the direction of the arrow shown in Fig. 1, while the cutter revolves in the direction shown by the arrow in Fig. 3. 30 Thus the ends of the spokes will be successively carried into the teeth of the rotary cutter-head which trims or cuts off the ends at the required length and at uniform length for every spoke. If any of the spokes should be 35 out of line, the inclined guide-rails *f* and *d* will carry the spoke to the proper place for cutting—that is, resting with its end on the stationary knife-block *G*. It is obvious that by the manipulation of the set-screw *X* the 40 wheel-support can be adjusted accurately to cut the spokes off at the desired length, and by constructing the machine of suitable size sufficient adjustability is provided to use the machines for wheels of all sizes.

45 What I claim as my invention is—

1. In a machine for the purpose described, the combination of a rotary cutter-head provided with peripheral cutting-teeth, with a stationary knife-block operated in connection 50 therewith, an adjustable wheel-support, and a rotary shaft positively and automatically operated from the mechanism actuating the said cutter-head, substantially as described.

2. In a machine for the purpose described, 55 the combination of the rotary cutter-head, the stationary knife-block operating in connection therewith, and an adjustable wheel-support provided with a rotary shaft and dog to rotate the wheel.

3. In a machine for the purpose described, 60 the combination of the rotary cutter-head provided with peripheral teeth, the stationary cutting-block adjusted in proximity to said teeth, the slidingly-adjustable wheel-support provided with a rotary wheel-carrier, and the 65 guide-rails for guiding the spokes to the rotary knife, all arranged substantially as described.

4. In a machine for the purpose described, 70 the combination, with the bed of the machine provided with a longitudinal slot, *I*, of the rotary cutter-head mounted at one end of the bed, the stationary cutting-block mounted upon the bed in proximity to the cutter-head, the wheel-support consisting of the bearings 75 *J*, slidingly adjustably engaging with the slot of the bed and provided with the adjusting-screw *X*, and the rotary shaft *L*, provided with a dog, *M*, substantially as described.

5. In a machine for the purpose described, 80 the combination, with the bed provided with the longitudinal slot *I*, of the rotary shaft *C*, the rotary cutter-head *F*, mounted thereon and provided with the peripheral cutting-teeth *a*, the stationary cutting-block *G*, 85 mounted upon the bed in proximity to the rotary cutter-head, the slidingly-adjustable wheel-support mounted upon the bed and carrying the rotary shaft *L* and dog *M*, the guide-rails *d* and *f*, the drive-connection between the shaft *C*, and the rotary shaft of the 90 wheel-support, all substantially as described.

6. In a machine for the purpose described, 95 the combination, with the bed of the machine and the longitudinal slot *I* formed therein, of the rotary shaft *C*, mounted in suitable bearings thereon, the rotary cutter-head *E*, secured to said shaft and provided with the peripheral cutting-teeth *F*, the knife-block *G*, mounted upon the bed, the slidingly-adjustable wheel-support, the shaft *L* and dog *M*, mounted upon said wheel-support, the pulleys 100 *N* and *P*, carried by the wheel-support, the pulley *Q*, mounted upon the shaft *C*, the pulleys *R* and *S*, stationarily mounted below the 105 shaft *C*, the pulley *U*, adjustably mounted below the bed and provided with the adjusting-screw *W*, and the endless cord *V*, all the parts being arranged to operate substantially as and for the purpose described.

110 In testimony whereof I affix my signature, in presence of two witnesses, this 27th day of September, 1888.

PETER GENDRON.
